UNITED STATES PATENT OFFICE.

ALFRED J. KIRSTIN, OF ESCANABA, MICHIGAN, ASSIGNOR TO A. J. KIRSTIN COMPANY,
OF ESCANABA, MICHIGAN.

SLACK-TAKE-UP MECHANISM.

1,210,657.

Specification of Letters Patent.

Patented Jan. 2, 1917.

Application filed March 13, 1916. Serial No. 83,716.

To all whom it may concern:

Be it known that I, ALFRED J. KIRSTIN, a citizen of the United States, and resident of Escanaba, in the county of Delta and State of Michigan, have invented certain new and useful Improvements in Slack - Take - Up Mechanisms; and I do hereby declare that the following is a full, clear, and exact description thereof.

10 The present invention relates to new and useful improvements in slack take up mechanisms particularly adapted for use as stump pulling devices, and of the type embodied in Patents No. 1,143,713 granted to me June 22, 1915, and No. 1,148,906 granted to me August 3, 1915.

15 It is the object of the present invention to improve various features of the structure of my previous applications to facilitate the 20 operation thereof, particularly with respect to holding parts of the device in such relative position as to facilitate the initial association of or the detachment of the runner cable with the clamping heads.

25 A further object resides in the provision of an improved means for locking the cam plates which determine the leverage expected by the mechanism in various relative positions to procure various desired leverages.

30 A still further object resides in the provision of an actuating member for the cam plate structure which is adapted to serve also the function of holding various parts of the mechanism in locked relation in the 35 operation of initially associating the runner cable with or of detaching it from the clamping heads.

With the above and other objects and advantages in view, the invention resides more 40 particularly in the novel combination, arrangement and formation of parts more particularly hereinafter described and pointed out in the appended claims.

45 In the drawings: Figure 1 is a side elevation of the improved slack take up mechanism with parts thereof broken away to more clearly disclose the structure. Fig. 2 is a sectional view taken transversely on the line 2-2 of Fig. 1, and looking toward the inner clamping head. Fig. 3 is a longitudinal sectional view through the lever head, this view being taken on the line 3-3 of Fig. 1. Fig. 4 is a transverse sectional view through the lever head on the line 4-4 of Fig. 1. Fig. 5 is an elevational view of the

combined cam plate wrench and locking link.

Referring now more particularly to the accompanying drawings, the take up mechanism comprises generally as in my previous 60 applications, a lever head A, an inner clamping head B, adjustably pivotally connected with the head by links 5 and an outer clamping head C similarly connected to the lever head by links 6. The lever head comprises 65 a pair of bars 7 having their outer ends inwardly directed at 8 and their inner ends curved to form a socket 9 for carrying a handle bar 9', the end portion of the plate serving in conjunction with suitable securing bolts 10 passed through the said end portion to carry an intermediate bar 11. Journally passed transversely through the intermediate portions of the plates is the fulcrum shaft 12 which pivotally carries 70 75 an anchor clevis 13 embracing the plates and the ends of the shaft are extended outwardly of the clevis and flattened to fit in the hubs 14 of suitable cam plates 15, these plates being similar to the cam plates 80 of my later patent, and provided with the shaft receiving slots 16 extended arcuately from adjacent the hubs of the plates, but in the present structure the major portion of the peripheries of the cam plates coincide 85 with the arc of a circle having as a center the axis of rotation of the plates and to provide for locking of the plates in desired position relative to the lever head, one of the plates is provided in its arcuate periphery with a series of notches 17 and an adjacent lever head plate 7 carries a pair of lugs 18 between which is pivoted a locking dog 19 adapted to selectively engage in the notches, this dog being provided with an 90 angular handle portion 20 extending inwardly from adjacent its free end. Each of the plates 7 and 11 is provided with a pair of longitudinally extending slots 21, and in the present structure, to provide for a maximum 95 strength of the plates and to permit the pivots of the links to move close together as possible to provide for a minimum leverage under the most severe working conditions, the shaft 12 is offset rearwardly from 100 the slots.

Slidably rotatable in each series of respective slots 21 and the adjacent slots 16 of the cam plates are the pivot shafts 22 to each of which is pivoted the links of a respective 110

clamping head, the links 5 having at their ends outwardly offset heads 23 disposed on the respective shaft at the sides of the intermediate plate 11 and the links 6 having inwardly offset heads 24 similarly disposed on the other shaft. The shafts are locked against displacement transversely by a collar 25 disposed thereon between the cam plates and the plates 7 and carrying suitable locking means such as pins 26. Thus it is noted that an exceedingly compact lever head structure is provided and that the collar 25 and the link heads 23 and 24 fill the spaces between the various plates adjacent the shaft whereby the strength of the structure is materially increased.

Each of the clamping heads comprises a pair of side plates 27, which carry the pinnacles 28 of oppositely projecting cam levers 29 and between which is held the clamping blocks 30 engageable by the cams of the levers to clamp the runner cable 31 therebetween. The cam levers of each head are oppositely offset at their outer ends as in the usual manner and, to provide for adjustably connecting the respective links thereto. In the present structure pivot pins 32 are provided which are each passed through a respective link end and selectively passed through one of a series of openings 33 in the lever. The levers are normally urged to a locking position by springs 34 bearing thereagainst and connected with the head in the usual manner. Thus the normal manipulation of the device by reciprocating the main lever procures successive unlocking, outward sliding and holding operations of the heads, and it is noted that inward movement of the heads independently of the rest of the structure provides a non-clamping relation of parts in the head which permits the runner cable to be freely moved with respect to the heads. To procure this relation of parts with respect to both heads at such times as it is desired, each of the heads carries a sleeve 35 and a rod 36 is passed through both of these sleeves and secured by the pin 37 in the sleeve of the outer head the rod being normally slidable in the sleeve of the other head. To procure inward movement of both heads, however, the rod is provided with an opening 38 adapted to receive a pin for abutment with the sleeve 35. The inner end of this rod is adapted for connection with a hook 39 carried by the adjacent plate 7 and to facilitate this connection, a clevis member 40 is pivoted to the end of the rod and has an eye member 41 adjustably passed through its bight. Thus, upon engagement of the eye member with the hook, a clockwise rotation of the lever head will draw both of the clamping heads 3 inwardly to relieve the clamping action of the blocks 30 whereby the runner cable may be readily secured in place or detached. It is noted,

however, that the tendency of the body member would be to rotate back to a position in which the clamping heads would be in clamping relation, and to hold the lever against such movement, a hook 42 is carried by the outer one of the links 6 and this hook is engageable by an eye 43 adjustably carried by a link bar 44, the other end of which is enlarged and provided with a wrench aperture 45 which fits over the mouth of the outer bolt 10.

It is noted that one of the cam plate hubs is as in my previous structure squared and this hub is adapted to fit the wrench aperture of the link bar whereby the said bar may serve as the wrench for adjusting the cam plates, the bar thus serving a double function in the present device.

I claim:

1. In a slack take-up mechanism including a lever head, a clamping head, a fulcrum shaft, a pivot shaft slidable in the lever head and a link connecting the pivot shaft and clamping head, the combination of a cam plate pivoted to the lever head and engaged with the pivot shaft, a peripheral portion of the cam plate being curved coincident with the arc of a circle having the cam pivot as its center, and provided with a series of notches, and a pawl carried by the lever head and selectively engageable in said notches.

2. In a slack take-up mechanism including a lever, clamping heads pivotally connected at spaced portions therewith and a fulcrum member on the lever, the combination of a hook carried by the lever at one side of the fulcrum member, a rod connected with both clamping heads, a clevis member having its arms pivoted to the end of the rod adjacent the hook and a hook engaging member passed through the bight of the clevis member and adjustable therein.

3. In a slack take-up mechanism including a lever, clamping heads pivotally connected at spaced portions therewith and a fulcrum member on the lever, the combination of a hook carried by the lever at one side of the fulcrum member, a rod connected with both clamping heads, means for connecting the rod with the hook, and means for preventing pivotal movement of the lever relative to the clamping heads.

4. In a slack take-up mechanism including a lever, a fulcrum member on the lever, clamping heads, and links pivotally connecting the clamping heads to the lever at the sides of the fulcrum, the combination of a hook carried by the lever at one side of the fulcrum member, a rod connected with both clamping heads, means for connecting the rod with the hook, and a link adapted for securing to the lever and to one of the clamping head links to hold the lever against relative movement.

5. In a slack take-up mechanism including a lever, a fulcrum member on the lever, clamping heads, links pivotally connecting said heads to the lever at the sides of the fulcrum member, and a cam plate pivoted to the lever and connected with the links for adjusting their pivotal connections, a hook carried by the lever at one side of the fulcrum member, a rod connected with both 10 clamping heads, and means for connecting the rod with the hook, the combination of a

projection on the lever, a projection on one of the links, a hub carried by the cam member and a bar provided with a wrench aperture at one end adapted to engage either the 15 cam member hub or the lever projection and said bar being adapted at its other end to engage the projection of the link.

In testimony that I claim the foregoing I have hereunto set my hand at Escanaba, in 20 the county of Delta and State of Michigan.

ALFRED J. KIRSTIN.
